Inventor,
John Rau,
By Knight & Felt

UNITED STATES PATENT OFFICE.

JOHN RAU, OF CHICAGO, ILLINOIS, ASSIGNOR TO THE RAU NOVELTY COMPANY, OF SAME PLACE.

OIL-CAN.

SPECIFICATION forming part of Letters Patent No. 423,812, dated March 18, 1890.

Application filed June 10, 1889. Serial No. 313,703. (No model.)

To all whom it may concern:

Be it known that I, JOHN RAU, a citizen of the United States, residing at Chicago, in the county of Cook and State of Illinois, have invented certain new and useful Improvements in Oil-Cans, of which the following is a full, clear, and exact description, reference being had to the accompanying drawings, which form a part of this specification, and in which—

10 Figure 1 is a vertical longitudinal section of the improved oil-can, showing the valve seated; and Fig. 2 is a similar view showing the valve unseated. Fig. 3 is a horizontal section on the line 3 3, Fig. 1. Fig. 4 is a 15 perspective view showing some of the parts on a larger scale.

The present invention relates to oil-cans in general; but it is especially valuable when applied to that class of cans known as "feeders," its object being to improve and perfect the can of this class which is shown and described in United States Letters Patent No. 383,370, which were granted to me on the 22d day of May, 1888.

20 To this end the invention consists in certain features of novelty, which are particularly pointed out in the claims hereinafter, a can embodying it being first fully described with reference to the drawings, in which—

25 A represents the body of the can, having the customary handle B, nozzle C, and filling-orifice D, provided with a screw-cap d. The interior of the body A and nozzle C communicate through an opening E, back of which,

30 within the body, is a diaphragm F, having an opening G, through which the oil passes to opening E, and thence to the nozzle, as suggested by the arrow in Fig. 2. Around the opening G the metal of which the diaphragm

35 F is formed is spun or bent up into a flange H, which constitutes a seat for a valve I, pivotally connected to the forward end of a valve-stem J, consisting of a lever fulcrumed at any intermediate point to a bar W, and engaged

40 at its heel end by a push-rod M, which passes upward through the top of the can and is provided with a push-button O. The push-rod passes through a sleeve N, whose opposite ends are closed by caps U, having central per-

45 forations for the passage of said rod. A spring P, situated within the sleeve and bearing

against the cap U at the lower end of said sleeve, tends to hold the push-rod normally elevated by exerting its pressure upward against a shoulder T thereon.

55

Upon the top side of the valve I are a pair of perforated ears i, situated at sufficient distance apart to admit between them the flattened end of the valve-stem J, which is provided with an elongated perforation j. A pin p is passed through these perforations and pivotally connects the valve with its stem. The perforation j is of such size as to permit the valve to seat itself perfectly (by gravity) before any pressure is exerted upon it, and also to permit the rounded end of the stem to have contact with and bear upon the top of the valve at X, so that the pressure for holding said valve to its seat will be exerted directly upon the valve itself and not upon its pivot. It is obvious that the elongated perforation to which this action is due may be formed through the ears i, instead of through the stem, and I therefore desire to have it understood that so far as my

75

invention relates to this loose pivotal connection it is not, in its broadest sense, limited to the identical arrangement shown in the drawings. Normally, the valve is held firmly upon its seat by a V-shaped spring V, which bears

80

at its angle end V' upon the top side of the valve-stem, whence its two arms or branches extend downward to the under side of the bar W, are coiled several times around said bar, and extend rearward beyond it, their extremities being secured to the can at x x. This rod (or bar) forms a support for the valve-stem J; but said stem and bar are not rigidly connected together, as in my former

85

patent. On the contrary, the stem is fulcrumed to the rod, so that the latter is not moved by the movement of the former. To accomplish this, I secure to the top side of the rod W a metallic saddle S, having a pair of short standards or ears s, which are a suffi-

90

cient distance apart to admit between them the flattened portion J^x of the valve-stem, said ears and stem being perforated for the passage of a pin f, constituting the fulcrum of the valve-stem. This saddle consists, preferably, of a single casting of approximately

95

U shape, with its under side hollowed out, so

100

as to fit snugly the top side of the rod, to which it is secured by a single screw passing downward through a perforation formed through the lower part of the saddle between the ears. The saddle is thus effectually held against displacement, and as the portion J^x of the valve-stem fits snugly between the ears s said stem is held against lateral movement horizontally.

15 The portions w of the rod W which are surrounded by the coiled portions of the spring V are reduced in diameter, so that the coils are sunken below the surface of the rod. This enables the rod itself to bear against the bottom directly. If these coils were not countersunk, but allowed to rest upon the bottom of the can, their pressure and friction incident to the operation of the device would soon wear holes through the said bottom.

20 What I claim as new, and desire to secure by Letters Patent, is—

1. In an oil-can, the combination, with the body, the nozzle, and the perforated valve-seat presented inward, of a valve-stem consisting of a horizontal lever fulcrumed at an intermediate point and terminating at one end above the valve-seat, an outward-seating valve situated within the can and pivotally connected directly to the above-mentioned 25 end of the valve-stem, so as to depend from the under side thereof, a spring operating to force said valve down upon its seat, and a push-rod engaging the other end of the valve-stem, substantially as set forth.

30 2. In an oil-can, the combination, with the body, the nozzle, and the perforated valve-seat presented inward, said seat being inclined substantially as shown, of a valve-stem consisting of a horizontal lever fulcrumed at an intermediate point and terminating at one end above the valve-seat, an outward-seating valve situated within the can and pivotally connected directly to the above-mentioned 35 end of the valve-stem, so as to depend from the under side thereof, a spring operating to force said valve down upon its seat, and a push-rod engaging the valve-stem, substantially as set forth.

35 3. In an oil-can, the combination, with the body, the nozzle, and the perforated valve-seat, of a valve-stem consisting of a lever fulcrumed at an intermediate point, having at one end an elongated perforation, a valve having perforated ears, between which the perforated end of said stem fits, a pivot-pin passing through said perforations, a push-rod engaging the other end of said stem, and a spring operating to hold said valve normally on its seat, substantially as set forth.

40 4. In an oil-can, the combination, with the body, the nozzle, and the perforated valve-seat, of a valve-stem consisting of a lever fulcrumed at an intermediate point, having one of its ends flattened, and provided with an elongated perforation, a valve having a pair of ears, between which the flattened end of said stem fits, a pin passing through said perfora-

tions, a push-rod engaging the other end of said stem, and a spring operating to hold said valve normally on its seat, substantially as set forth.

45 5. In an oil-can, the combination, with the body A , the nozzle C , and the perforated valve-seat, of the valve I , the valve-stem J , to one end of which said valve is pivotally connected, so as to depend from the under side thereof, the rod W , resting upon the bottom of the can, upon which said stem is fulcrumed, so as to be capable of moving independently thereof, the spring V , bearing at one end upon the 50 valve-stem, coiled at an intermediate point around the rod W , and at the other end secured to the can, and the push-rod M , all constructed and arranged to operate substantially as and for the purpose set forth.

55 6. In an oil-can, the combination, with the body A , the nozzle C , and the perforated valve-seat, of the valve I , the valve-stem J , consisting of a lever fulcrumed at an intermediate point, to one end of which said valve is secured, the push-rod M , engaging the other end of said stem, the rod W , resting upon the bottom of the can and forming the support for the fulcrum of the valve-stem, and the spring V , bearing at one end upon said stem 60 and at the other end secured to the can, said spring having intermediate of its ends coils surrounding a contracted portion of said rod, substantially as set forth.

65 7. In an oil-can, the combination, with the body A , the nozzle C , and the perforated valve-seat, of the valve I , the valve-stem J , to one end of which said valve is secured, the push-rod M , engaging the other end of said valve-stem, the rod W , resting upon the bottom of the can, the saddle S , secured to said rod and on which the stem is fulcrumed, and the spring V , bearing at one end upon the valve-stem, coiled at an intermediate part around the rod W , and at the other end secured to the can, substantially as set forth.

70 8. In an oil-can, the combination, with the body A , the nozzle C , and the perforated valve-seat, of the valve, the valve-stem, the push-rod, the rod W , resting upon the bottom of the can, the saddle S , to which the valve-stem is fulcrumed, having its under side hollowed out and fitting the rod W , and the spring V , bearing at one end upon the valve-stem, coiled at an intermediate part around said 75 rod W , and at its other end secured to the can, substantially as set forth.

85 9. In an oil-can, the combination, with the body A , the nozzle C , and the perforated valve-seat, of the valve-stem J , terminating at one end above the valve-seat and having the perforated flattened portion J^x , the valve I , pivoted to the above-mentioned end of the valve-stem, so as to depend from the under side thereof, the rod W , resting on the bottom of the can, the saddle S , secured to the rod W , and having the perforated ears s , between which fits the flattened portion J^x , the fulcrum-pin f , passing through said perfora-

tions, the spring V, bearing at one end upon the valve-stem, coiled at an intermediate part around the rod W, and at the other end secured to the can, and the push-rod M, substantially as set forth.

10. In an oil-can, the combination of the following elements, to wit: the body A, the nozzle C, the perforated valve-seat, the valve-stem J, having one end flattened and provided with an elongated perforation j, and having at an intermediate point the perforated flattened portion J^x, the valve I, having perforated ears i, between which the flattened end of the valve-stem fits, the pin p, passing through said perforations, the rod W, resting

upon the bottom of the can and having the contracted portions w, the saddle S, secured to said rod and having the perforated ears s, between which the flattened portion J^x of the stem fits, the fulcrum-pin f, passing through said perforations, the push-rod M, and the V-shaped spring V, bearing at one end V' upon the valve-stem, having its other end secured to the can, and having intermediate of its ends coils surrounding the contracted portions w of the rod W, substantially as set forth.
